(57) **CLAIM**

I claim the ornamental design for a snuffer tool, as shown and described.

DESCRIPTION

FIG. 1 is a perspective view of a snuffer tool, showing my new design;

FIG. 2 is a front elevational view of FIG. 1, the rear elevational view being a mirror image thereof;

FIG. 3 is a left-side elevational view of FIG. 1, the right-side elevational view being a mirror image thereof;

FIG. 4 is a top plan view of FIG. 1;

FIG. 5 is a bottom plan view of FIG. 1; and,

FIG. 6 is a cross-sectional view of FIG. 4, taken along line 6-6.

1 Claim, 2 Drawing Sheets**FIG. 1**

FIG. 2

FIG. 3

FIG. 4

FIG. 5

FIG. 6
